UNITED STATES PATENT OFFICE.

CHARLES A. DESPAIN, OF SPOKANE, WASHINGTON, ASSIGNOR TO W. B. CAMPBELL, OF SPOKANE, WASHINGTON.

ROTARY PUMP.

1,125,901.

Specification of Letters Patent.

Patented Jan. 19, 1915.

Application filed January 21, 1914. Serial No. 813,511.

To all whom it may concern:

Be it known that I, CHARLES A. DESPAIN, a citizen of the United States, residing at Spokane, in the county of Spokane and State of Washington, have invented certain new and useful Improvements in Rotary Pumps, of which the following is a specification, reference being had to the accompanying drawings.

10 This invention relates to certain improvements in rotary pumps; and the object of the invention is to provide a device of this general character having novel and improved means whereby the rotor, included 15 therein, may be operated with convenience and facility.

A further object of the invention resides in providing a device of this character in which the blades thereof are arranged on 20 the rotor in an improved manner, whereby to give the best results with a simple and inexpensive construction.

Still another object of the invention resides in providing a device which is simple 25 and durable in construction, inexpensive to manufacture and one which will be very efficient and useful in operation.

With these and other objects in view, the invention consists in the novel features of 30 construction, combination and arrangement of parts as will be hereinafter referred to and more particularly pointed out in the specification and claims.

In the accompanying drawings forming a 35 part of this application, Figure 1 is a vertical longitudinal section through a pump constructed in accordance with my invention. Fig. 2 is a transverse section therethrough as seen on line 2—2, Fig. 1. Fig. 40 3 is an end elevation of one of the blades removed. Fig. 4 is a front elevation of the same. Fig. 5 is an elevation of another of the blades used in the device. Fig. 6 is a side elevation thereof; and Fig. 7 is a similar 45 view of another of the blades.

In describing my invention, I shall refer to the drawings in which similar reference characters designate corresponding parts throughout the several views and in which—

50 1 indicates the main body or housing of a pump supported on the legs 2 and having the one side thereof open. The rear wall of the housing or casing is provided with a recessed extension 3 in which is provided a

central opening 4 and formed on the outer 55 face of the extension 3, is an annular flange 5, in which is adapted to be applied a packing so as to form an oil-proof bearing for a purpose to be hereinafter and more particularly described. The periphery of the housing or casing 1 is provided with an inlet 6, and a discharge opening 7 is provided in the periphery a short distance from the opening 6 therein. The housing or casing 1 is also offset somewhat, as shown at 8 at a 65 point therein which is directed toward the discharge opening 7 so as to afford a complete discharge channel therein, as will be seen from the following description.

I have provided a rotor for coöperation 70 with the casing, the same comprising a central shaft 9 which extends through the opening 4 in the wall of the extension 3 and through the oil-proof bearing formed by the packing in the annular flange 5. A gland 75 or the like is also provided in connection with this bearing to retain the packing in place and provide a positive oil-proof bearing at this point. The main portion of the rotor consists of a drum-like member 10, one 80 side wall of which is open and formed on the remaining wall thereof is a hub-like member 11 which is received in the recess of the projection 3 to rotate in the latter. The shaft 9 extends through a bore in this portion 85 11 and is keyed to the latter, whereby said rotor proper may rotate with the shaft 9. A disk-like member having a central opening therein or what may be termed an annulus 12, is applied to the open side of the 90 drum-like rotor 10, the same being removably secured by means of screws 13 to the peripheral edge of said member 10, as clearly shown in Fig. 2 of the drawings. The periphery of this drum-like member 10 95 is provided at regular intervals with slots 14 through which are slidably disposed the blades 15. Formed on the inner wall of the periphery of the drum 10, are the inwardly disposed spaced lugs 16 between which the 100 blades are guided so as to provide a greater bearing surface against which the blades may contact in the movement thereof inwardly and outwardly with respect to said rotor proper. As shown in the drawings, 105 there are three of such blades 15, working through three slots 14 and the outer edges of these blades are adapted to contact with

the inner wall of the periphery of the member 1, while the side edges of the blades contact with the side walls thereof.

It must be here stated that the shaft 9, while extending centrally through the drum-like rotor 10, is disposed eccentrically through the main housing or casing 1 and in view of this construction, it will be seen that in order to permit the outer ends of the blades to constantly contact with the inner wall of the periphery of the member 1, a means must be provided for the actuation of said blades during the rotation of the rotor in said casing or housing 1. I have provided for this actuation of the blades and, to this end, each blade is provided with a shank portion or the like 17, and each shank has an elongated closed loop or eye 18 formed thereon, the same extending in a plane at right angles to the plane of the faces of the blade proper. The shaft 9 extends through these closed loops or elongated eyes 18 and does not contact with the same, as will be seen from the following description. It must be stated, however, that the shanks 17 of the blades 15 are not formed on the blades in the same position thereon. The one blade has the shank 17 formed centrally thereof; a second blade has the shank 17 formed at the one side edge thereof, while the other blade has the shank 17 formed at the opposite side edge of the same. In this manner, the closed loops or elongated eyes 18 may be brought in actual contact with one another and all of the blades 15 properly disposed through the slots 14 in the periphery of the rotor 10. In other words, the shanks are properly offset with respect to one another and with respect to the blades carrying the same, so as to permit said shanks to be brought into contact with one another and, at the same time, permit the blades to be operatively disposed in their proper positions in the rotor.

The outer head or cap blade 19 is provided for application to the open end of the housing or casing 1, the same being slightly enlarged, as shown at 20 to be entered in the central enlarged opening of the member 12. The shaft 9, of course, passes through a central opening in this member 19 and a bearing 21 is provided on the outer face of this member to properly receive the shaft therein. Also formed on the inner face of the portion 20 of said member 19, is a boss 22, which is received in the loops or elongated eyes 18 of the blades 15. The shaft 9 extends through this portion 22 but eccentric with respect thereto and the periphery of the member 22 is covered with a wear sleeve 23. It will be seen from this construction that as the rotor is caused to rotate in the housing or casing 1, the blades will be rotated therewith but in view of their connection with this boss 22, said blades will be reciprocated in the slots of the rotor as the latter is rotated. The parts are arranged in such relation to one another, however, that the blades 15 will be drawn inwardly when approaching the upper portion 70 of the housing or casing. This is necessary in view of the eccentric disposition of the rotor in the casing 1.

In the operation of the device, assuming that the same is completely set up for use, a fluid such as water, is adapted to enter the casing or housing 1, through the inlet opening 6 therein. This fluid being directed against the adjacent blade 15, will cause the rotor to be revolved in the casing, thus also causing the shaft 9 to be rotated. As stated, the blades 15 are constantly in engagement with the walls of the casing or housing 1 and the fluid directed thereagainst will find a positive wall or resisting member. As the pressure against this wall or resisting member increases, the rotor will obviously be revolved and the fluid carried upwardly therewith toward the discharge opening. In the rotation of the rotor, the blades approaching the discharge opening are adapted to be forced inwardly and at points adjacent the inlet opening, said blades are adapted to be forced outwardly, such action being capable in view of the connection between the boss 22 and the elongated ribs or eyes 18 engaged with said boss. As the rotor continues in its operation the fluid entering the opening 6 and causing the rotation of the rotor will be directed upwardly 100 around the rotor and discharged through the opening 7. This operation may be continued and the power applied to the shaft 9 may be transmitted for the operation of any desired device (not shown). Should for any reason whatsoever it is desired to remove a blade or any number of the blades 15, it is only necessary to remove the outside cap blade 19 and the annulus or disk-like member 12. By the removal of these members 12 and 19, any one or all of the blades 15 may be removed from the shaft 9 and replaced by others, if desired, without the entire removal of the rubber from the member 1.

From the foregoing it will be seen that I have provided a device which is simple and durable in construction, inexpensive to manufacture and one which will be very efficient and useful in operation, and while I have particularly described the elements best adapted to perform the functions set forth, it is obvious that various changes in form, proportion and in the minor details of construction may be resorted to without departing from the spirit or sacrificing any of the principles of the invention.

Having thus described this invention, what I claim is:—

1. A rotary pump of the class described 130

comprising a housing having inlet and outlet openings therein, one wall of said housing being provided with a boss, a hollow rotor arranged in said housing to rotate eccentrically therein, a plurality of blades carried on the rotor and movable inwardly and outwardly with respect thereto, said blades being designed to contact with the walls of the housing, inwardly directed spaced lugs carried by the rotor and between which the blades are directed, means formed on said blades designed to coöperate with the boss on the one wall of the housing to actuate said blades inwardly and outwardly as the rotor revolves in the housing.

2. A rotary pump of the class described comprising a housing of substantially cylindrical design having inlet and outlet openings therein, one wall of said housing being provided with a boss disposed within the interior thereof, a rotor of drum-like design arranged to rotate eccentrically within the housing, a plurality of blades carried by the rotor and adapted to slide inwardly and outwardly through the periphery thereof to contact with the walls of the housing, inwardly directed spaced lugs carried by the rotor and between which the blades are directed, and elongated loops formed on the inner ends of the blades disposed within the rotor to coöperate with a boss on the one wall of the housing, whereby to actuate said blades inwardly and outwardly as said rotor revolves in the housing.

3. A rotary pump of the class described comprising a housing of substantially cylindrical design having inlet and outlet openings therein, one wall of said housing being provided with a boss disposed within the interior of said housing, a rotor of drum-like design arranged to rotate eccentrically within the housing, the periphery of said rotor being provided with slots, blades arranged to slide through the slots of said rotor designed to contact with the walls of the hous-

ing, inwardly directed spaced lugs carried by the rotor and between which the blades are directed, and elongated loop members formed on the inner ends of said blades within the rotor and receiving said boss 50 therein, whereby to actuate said blades inwardly and outwardly with respect to the rotor as the latter revolves in the housing.

4. In a rotary pump of the class described, the combination with a substantially cylindrical housing having inlet and outlet openings therein, one wall of said housing being removable and provided with an inwardly extending boss, the opposite wall of said housing being provided with a recess arranged centrally therein; of a rotor comprising a substantially hollow and cylindrical body, one wall of which is provided with a projection received in the recess of the wall of said housing, the periphery of said drum-like body being provided with slots arranged at predetermined points therein, a shaft rotatably mounted in the walls of the housing and keyed to the projection of the drum-like body of the rotor, a plurality of 70 blades slidably disposed through the slots in the periphery of the body of the rotor and designed to contact with the walls of the housing, inwardly directed spaced lugs carried by the rotor and between which the 75 blades are directed, and elongated loops formed on the inner ends of said blades and receiving the shaft and the aforesaid boss therethrough, the engagement of the boss with the loops of the blades causing the latter to be disposed inwardly and outwardly with respect to the rotor as the latter is revolved in the housing.

In testimony whereof I hereunto affix my signature in the presence of two witnesses. 85
